UNITED STATES PATENT OFFICE.

FREDERICK H. CRAFTS, OF ROCHESTER, NEW YORK.

DESIGN FOR A TOOL FOR WORKING PLASTIC MATERIAL.

SPECIFICATION forming part of Design No. 24,893, dated November 12, 1895.

Application filed March 14, 1895. Serial No. 541,811. Term of patent 14 years.

To all whom it may concern:

Be it known that I, FREDERICK H. CRAFTS, of Rochester, in the county of Monroe, in the State of New York, have invented a new and useful Design for a Tool for Working Plastic Material, of which the following, taken in connection with the accompanying drawings, is a full, clear, and exact description.

Figure 1 is a side elevation of a tool for working plastic material embodying my design. Fig. 2 is a vertical sectional view taken on line 2-2, Fig. 1; and Fig. 3 is a top plan view of a tool embodying my invention, these views being deemed necessary to fully illustrate the design.

The leading feature of my design consists in an elongated body having its top and bottom faces formed with substantially parallel intermediate portions and upturned extremities, a handle projecting upwardly from said top face, and a substantially central longitudinal rib projecting downwardly from said bottom face and formed with the intermediate portion of its lower edge substantially parallel with the corresponding part of the bottom face and its extremities upturned, and having one side face formed concave in cross-section and its opposite side face formed substantially flat and arranged at right angles with said bottom face.

A is the longitudinal body of a tool embodying my design, and B C are respectively the handle and longitudinal rib projecting from its top and bottom faces a a'. The body A is of greater length than width, and its top and bottom faces a a' are substantially flat transversely and are formed with substantially parallel intermediate portions a² and upturned ends a⁴. The side and end faces a⁵ a⁶ of the body A are arranged at substantially right angles with each other and are

united by rounding corners a⁷, and the lower edges of the faces a⁵ are slightly rounded transversely.

The handle B projects upwardly from substantially the central part of the intermediate portion a⁸ of the top face a, and is formed with a cylindrical lower extremity b, a rounding upper extremity b', and intermediate portions b² b³, formed, respectively, with concave and convex outer faces.

The longitudinal rib C is arranged substantially central with the lower face a' and projects downwardly therefrom. The intermediate portion c of the lower edge of the rib C is substantially parallel with the corresponding parts of the faces a a', and the opposite ends c' of said edge are upturned in planes substantially concentric with those of the extremities of said faces a a'. One side face c² of the rib C is formed concave in cross-section, and its opposite side face is arranged at substantially right angles with the face a.

A tool embodying my design has a pleasing and characteristic appearance, and is used in the formation of cement and artificial-stone walks and in the manipulation of plastic materials.

What I claim is—

The design for a tool for working plastic material, substantially as herein shown and described.

In testimony whereof I have hereunto signed my name, in the presence of two attesting witnesses, at Syracuse, in the county of Onondaga, in the State of New York, this 28th day of December, 1894.

FREDERICK H. CRAFTS.
